Primary Examiner — Joseph Kukella(74) *Attorney, Agent, or Firm* — Polson Intellectual Property Law; Margaret Polson(57) **CLAIM**

The ornamental design for a climbing structure as shown and described.

DESCRIPTION

FIG. 1 is an isometric view of our new climbing structure.

FIG. 2 is a front side elevation view thereof.

FIG. 3 is a back side elevation view thereof.

FIG. 4 is a left side elevation view thereof.

FIG. 5 is a right side elevation view thereof.

FIG. 6 is a top view thereof; and,

FIG. 7 is a bottom view thereof.

The features shown in broken lines in the drawings depict environmental subject matter only and form no part of the claimed design.

1 Claim, 7 Drawing Sheets(56)
